UNITED STATES PATENT OFFICE.

J RAYMOND PLANK, OF GRAND RAPIDS, MICHIGAN, ASSIGNOR TO WOLVERINE BRASS WORKS, OF GRAND RAPIDS, MICHIGAN, A CORPORATION OF MICHIGAN.

QUICK-ACTION CHUCK.

Application filed November 10, 1917, Serial No. 201,383. Renewed February 3, 1923.

To all whom it may concern:

Be it known that I, J RAYMOND PLANK, citizen of the United States of America, residing at Grand Rapids, in the county of 5 Kent and State of Michigan, have invented certain new and useful Improvements in Quick-Action Chucks; and I do hereby declare the following to be a full, clear, and exact description of the invention, such as 10 will enable others skilled in the art to which it appertains to make and use the same.

This invention relates to a quick action chuck adapted for use in holding drills, 15 taps, reamers and like tools which may be driven in any suitable drill press or like machine, the chuck of the present invention being designed so that a drill or like tool may be quickly disconnected from the driving spindle or socket member in which 20 it is located at any time, the spindle or socket member continuing its rotation while the drill or like tool is freed from engagement therewith. The invention is directed especially to the attainment of these ends 25 and comprises various novel constructions and arrangements of parts for attaining the same as well as many other novel features which will be apparent as understanding is had of the construction from the following 30 description.

The drawings show preferred forms of my invention and in said drawings;

Fig. 1 is an elevation of the chuck.

Fig. 2 is an elevation of the socket member adapted to receive an end of a drill or like tool.

Fig. 3 is a vertical sectional view taken through the construction shown in Fig. 1.

Fig. 4 is a section taken substantially on 40 the line 4—4 of Fig. 2.

Fig. 5 is an elevation of the connecting end of a drill or like tool adapted to be used with the chuck.

Fig. 6 is a section on the line 6—6 of 45 Fig. 5.

Figs. 7 and 8 are, respectively, plan and side views of a pair of locking dogs forming elements of the chuck.

Fig. 9 is a view similar to Fig. 1 of a 50 modified form of chuck.

Fig. 10 is a vertical sectional view there-through.

Fig. 11 is a vertical sectional view through the socket member.

Fig. 12 is a plan view of the chuck shown 55 in Fig. 9.

Fig. 13 is a horizontal section on the line 13—13 of Fig. 10, and

Fig. 14 is a view, similar to Fig. 5, of a slightly modified form of drill or simi- 60 lar tool.

In the drawings like reference characters refer to like parts and the sectional views, Figs. 4, 6 and 13 are taken looking in the directions indicated by the arrows associated with section lines 4—4, 6—6, and 13—13, respectively.

In construction socket member 1 is of cylindrical form and is interiorly bored from its lower end to provide a longitudinal cylindrical opening 2 into which the upper end of a drill, reamer, or like tool 3 may be freely inserted. Said socket member may be connected in any desired manner to the driving spindle or a drill press 70 whereby when the press is in operation the socket member is continually rotated. The upper end of the drill of tool 3 is of special formation it having a substantially semi-spherical head 4 formed with a bevel, 80 as indicated at 5, adjacent its under side and, immediately below the head, the drill is reduced in diameter and has parts cut away at each side whereby a section 6 is formed having opposed flat parallel sides 85 7 as best shown in Fig. 6. A passage 8 is made through the socket 1 from the upper end of the boring or recesses 2 whereby air is free to enter or pass out through this opening on removal or entering the tool into 90 the socket.

A housing in the form of an annular ring 9 is positioned around the socket 1. On its inner sides and adjacent its upper end the housing has a relatively short vertical 95 cylindrical face 10 from the lower part of which an annular downwardly and outwardly extending face 11 continues which meets and joins with a second inner cylindrical face 12 having a diameter larger 100 than the face 10 and from the lower part of which a downwardly and inwardly extending inclined annular face 13 continues which meets a third cylindrical face 14 of less height than either the faces 10 or 12 105 and of a diameter intermediate in size being greater than that of the face 10 and less than that of the face 12 as shown in

Fig. 3. At its upper end the housing has an opening which freely passes the socket member 1. A cover 15 also having an opening for the socket member is fitted in and closes the lower end of the housing.

Two chuck jaws or dogs 16 are located on opposite sides of the upper end of the drill or other tool 3. These dogs at their outer ends have curved faces 17 struck with substantially the same radius as the face 10 and at their inner ends are bevelled as indicated at 18 at both the upper and lower edges. The socket member 1 has opposed openings 19 in its sides through which said jaws pass and the distance between the body of the drill or similar tool 3 and its head 4 is such that the inner ends of the jaws may pass freely therebetween.

In practice when the drill is inserted in the opening 2 and the chuck occupies its normal position, the curved inner face 10 of the housing 9 bears against the outer curved faces 17 of the jaws 16 and forces them inwardly so that their inner ends engage with the parallel flat sides 7 of the part 6 of the tool. The housing rests upon outer ends of the jaws 16. In this position as shown in Fig. 3 the drill is secured to and must rotate with the socket member. Housing 9, however, is free to move upwardly and if at any time it is desired to remove the drill entirely from the socket the housing 9 may be grasped by hand and elevated so that the ends of jaws 16 may move outwardly 35 into the larger space inside of the housing bounded by the cylindrical face 12. When this occurs jaws 16 may be moved back sufficiently to disengage entirely from the tool and it may be removed and another inserted 40 without stopping the rotation of the socket member. If, however, as many times occurs, it is desired that the drill or similar tool shall be stopped but not entirely removed from the machine, housing 9 is elevated as 45 far as possible whereupon the jaws 16 do not entirely disconnect from the tool but can move outward only as far as permitted by the lower inner cylindrical face 14 of the housing. In such case the inner ends of the 50 jaws 16 project slightly through the openings 19 of the socket member so that the bevelled face 5 of head 4 rests upon the inner ends of the jaws, this preventing the withdrawal of the tool but permitting it to 55 stand still while the socket member and connected jaws freely rotate. This is desirable at times especially in the drilling of metal where the drill is about to break through or where it strikes a fault or blow hole in 60 the metal such that the drill feeding too fast is liable to catch a lip of metal which resists the turning thereof. The operator of the drill or other tool by quickly lifting the housing 9 frees the drill from driving engagement with the socket so that breakage 65

or other injury to the drill is safe-guarded against.

In Figs. 9 to 14 inclusive the construction is very similar except that the housing 9^a has only the two interior faces 10^a and 12^a 70 instead of three faces corresponding to the face 10, 12, and 14 in the first modification described. The socket 1^a tool 3^a, dogs 16^a and closing plate 15^a for the housing are substantially the same as 75 previously described. The head 4^a of the tool instead of being semi-spherical in outline is more in the nature of frustro-conical outline but is equivalent in every respect to the head 4 previously described. With this 80 chuck the quick connection and disconnection of the tool only is attained there being omitted the construction by means of which free rotation of the socket member with respect to the tool, with the tool retained in 85 the socket, is effected.

A chuck of the character described is of value especially in saving time in changing drills, taps, reamers, or like tools in drill presses. Ordinarily it is necessary to stop 90 the driving spindle whenever a change in tools is to be made. Furthermore with the construction in Figs. 1 to 8 inclusive insurance against breaking or other injury to the tool may be had without entirely disconnecting the tool. The chuck is of simple construction and may be readily manufactured and assembled at comparatively low 95 cost.

I claim:—

1. In combination, a socket member internally bored to permit the entrance of a drill shank or similar member and provided with a plurality of openings through the sides thereof, said openings having parallel upper and lower sides and parallel vertical sides, a dog seated in each opening and freely movable radially with respect to the socket member in said opening, said dogs each having an outer curved end, parallel upper and lower sides, parallel vertical sides at its inner portion and angularly positioned vertical sides at their outer portion to limit their inward movement, and each dog at its inner end being formed with a vertical face lying in a plane at right angles to the planes of the upper and lower sides and the inner portions of the vertical sides of the dog, an annular housing member 100 loosely mounted around the socket member and adapted to move lengthwise thereof, said housing member being formed with an inner cylindrical face having substantially the same radius of curvature as the outer 105 ends of said dogs and adapted to bear against said outer ends thereof and force the dogs to inner position, and also provided with a second inner cylindrical face of 110 larger diameter than the first face, there being an annular conical face connecting the 115

100

105

110

115

120

125

130

two cylindrical faces, substantially as described.

2. A device containing the elements in combination defined in claim 1, combined with integral means closing the upper end of the housing member having an opening permitting the passage of the socket member, said means by engagement with the outer ends of the dogs at their upper sides limiting the movement of the housing member along the socket member and preventing disengagement therefrom in a downward direction, and a plate attached to and closing the lower end of the housing member having an opening to pass the socket member and similarly engaging with said dogs to prevent disengagement on upward movement of the housing member.

3. In combination a cylindrical socket member adapted to receive the shank of a

drill or similar tool, dogs loosely mounted in openings through the sides of said socket member, a housing member around the socket member and loosely mounted to freely move around and lengthwise thereof, said member being formed interiorly with an upper cylindrical face, an intermediate cylindrical face of larger diameter and a lower cylindrical face having a diameter of a size between that of the first mentioned faces, together with annular conical interior faces connecting said cylindrical faces, substantially as described.

4. A mechanism as claimed in claim 3 combined with a plate placed loosely around the socket member and closing the lower end of the housing member, substantially as described.

In testimony whereof I affix my signature.

J RAYMOND PLANK.
